UNITED STATES PATENT OFFICE.

CHRISTEN ANDERSEN, OF HURUP, DENMARK.

COMBINED WRENCH AND PIPE-TONGS.

1,395,785.

Specification of Letters Patent. Patented Nov. 1, 1921.

Application filed July 23, 1919. Serial No. 313,672.

To all whom it may concern:

Be it known that I, CHRISTEN ANDERSEN, a subject of the King of Denmark, and resident of Hurup, in the State of Denmark, 5 have invented certain new and useful Improvements in Combined Wrenches and Pipe-Tongs, of which the following is a specification.

The present invention concerns a combined wrench and pipe-tongs of the following description. A nut is placed in the hole of a spanner shaft, which carries one jaw, a spindle passes through the hollow of the wrench shaft and the nut, and is connected with the other jaw so as to make it possible to vary the span of jaw. Wrenches of this description have several defects, *e. g.*, it is generally difficult to adjust the jaws so as to fit on the nut; if the span be too small, 10 the jaws will not slide on the nut; if it be too large the jaws will slide over the edges of the nut and spoil them, and yet not turn, besides it is troublesome and will take some time to decrease and increase the span of 15 jaw to any considerable extent, as it is only possible to touch a small part of the nut, *i. e.*, the part projecting over the wrenchshaft. The first defect is remedied by the present invention, as the jaw of the 20 wrench shaft can be adjusted parallelly in relation to the adjustable jaw, the second defect by an arrangement, by means of which that part of the wrench shaft surrounding the nut that varies the span of 25 jaw can be turned away from the nut, and consequently partly disclose it, and thus the nut may pass up and down the spindle without disarranging it.

The invention is seen on the drawing in 40 one mode of construction:

Figure 1 shows a side-view of the wrench with the jaws in closed position.

Fig. 2 a side-view of the wrench set on a nut,

45 Fig. 3 the same viewed from the side, and the lower part of the wrench shaft turned aside,

Fig. 4 the same viewed from above, and

50 Fig. 5 a section of the movable jaw of the wrench shaft on the line A—A in Fig. 3.

1 is the wrench shaft, made in the ordinary way of a folded steel plate and joined to a connecting piece 2, thus forming a guide for an adjustable bar 3 of rectangular section 55 having at one end a jaw 4, which is provided with saw-teeth 5—6—7— and at the

other end a spindle 8 provided with a screw-thread and a circular nut 9, which may be turned in a hole 21 of the wrench shaft 1. The section of the connecting piece 60 2 is at the top shaped like a cross, Fig. 5, thus forming a rest for the jaw, 10 which is U-shaped and provided with the saw-teeth 11—12—13—. The rests between jaw 10 and the connecting piece 2 form an angle with 65 jaw 4, so that the span of jaw will be decreased or increased by moving the jaw, 10 of the connecting piece 2. Jaw 10 can be adjusted by means of a double armed-lever 14, the fulcrum of which is pin 15 in wrench 70 shaft 1. One arm 22 of the lever 14 is by means of a pin 16 connected with jaw 10, while the other arm 23, is worked upon by a spring 17, in such a manner that jaw 10 will automatically decrease the distance 75 between itself and jaw 4. In order to prevent jaw 10 from falling from the connecting piece 2 a pin 18, movable in an oblong hole in the connecting piece 2, is carried through jaw 10. The lower part 19, of the wrench 80 shaft 1 is movable around a pin 20, thus making it possible to partly disclose the nut 9, because two of the conterminous sides, which form the hole 21, for the nut 9, are formed by the lower part 19, of the wrench 85 shaft 1.

It will be apparent from the foregoing description that the object of providing the shiftable end member 19 is to enable facility of adjustment of the sliding jaw 4. Thus, 90 when it is desired to open the wrench from its full closed position to any considerable extent, instead of turning the nut 9 by the finger and thumb, which process would be rather slow, the part 19 is shifted to the position shown in Fig. 3 leaving the nut 9 in such accessible position as to permit it to be quickly run along the threaded shank 8. This action is in the nature of a spinning 95 action of the nut which is not obtainable when it is operable with the shiftable piece 19 in the closed position of Figs. 1 and 2. When the general adjustment desired is reached, piece 19 is returned to its normal closed position in which position the nut 100 and the shiftable jaw is held relatively fixed. Likewise, when it is desired to close the jaws of the wrench this may be also quickly accomplished by again opening the part 19 and allowing the jaw 4 to slide into 110 its closed position freely. The nut 9 may be quickly run along the shank 8 in the oppo-

site direction and the part 19 finally returned to its normal position. It will furthermore be apparent that the fine adjustments of the wrench jaws are obtainable in 5 two different ways, one by the screwing of the nut 9 and the other by the operation of the slideable jaw 10 through the lever 23. When making the adjustment the operator's hand is engaged around the lever 23 to pull 10 the jaw 10 outwardly and when the general adjustment of the jaws on the object is obtained the lever 23 is released, permitting the jaw 10 to move inwardly on its angle guide piece, thus effectively gripping the 15 object. The greater the stress imparted to the object operated upon, the greater the pressure of the jaw 10 against said object. An invention of this character is very effective as a pipe wrench having in view this 20 operation of the jaws.

What I claim is:

1. In a wrench of the class described, a handle, a jaw slidably mounted for movement longitudinally of the handle and having a threaded shank, a nut on said shank 25 for adjusting the jaw as aforesaid, a second jaw slideable transversely of the handle and first mentioned jaw, a lever connected

to the transversely sliding jaw for actuating the same, spring means coöperating with 30 the lever and tending to shift the transversely sliding jaw toward the handle, and a movable section on the handle coöperating with the shank nut to hold the longitudinally sliding jaw in adjusted position, said 35 section being shiftable to free the last mentioned jaw for movement.

2. In a wrench of the class described, a handle, a jaw slidably mounted thereon for movement longitudinally of said handle, said 40 jaw having a threaded shank and a nut thereon coöperative with the handle for imparting the longitudinal movement aforesaid, a second jaw slideable transversely of the handle, a lever connected to said second 45 jaw for actuating the same and fulcrumed on the handle, a pivot pin on which said lever is fulcrumed, the end of the lever having pivotal connection with the slideable jaw, and a further connection intermediate the 50 slideable jaw and the handle for guiding the jaw in its movements under the actuation of the lever.

In testimony whereof I affix my signature.

CHRISTEN ANDERSEN.
